UNITED STATES PATENT OFFICE.

PATRICK COMERFORD, OF VICTORIA, BRITISH COLUMBIA, CANADA, ASSIGNOR TO
SAFETY FIRST AIR BRAKE COMPANY, OF SEATTLE, WASHINGTON.

AIR-BRAKE SYSTEM.

1,138,193.

Specification of Letters Patent.

Patented May 4, 1915.

Application filed April 11, 1913. Serial No. 760,559.

To all whom it may concern:

Be it known that I, PATRICK COMERFORD, a citizen of Canada, and a resident of Victoria, British Columbia, Canada, have invented certain new and useful Improvements 5 in Air-Brake System, of which the following is a full, true, and exact specification.

This invention relates to air brake systems, and has for its principal object to generally 10 improve and simplify the same, to the end that an application of the brakes, sufficient to stop the entire train, can at all times be made, so long as there is air in the main reservoir, despite previously repeated applications 15 of the brakes and the resultant depletion of the air within the auxiliary reservoirs; that a single engineer's valve only is necessary, which is common to both the automatic and the straight air portions of the 20 system; that unavoidable leakages in the joints of the train pipes are compensated for so that accidental intermittent applications of the brakes is effectually prevented.

Other objects and features will appear as 25 the invention is more fully hereinafter described, illustrated in the accompanying drawings and pointed out in the appended claim.

In the drawings Figure 1 is a diagrammatic plan view, of that portion of the system 30 which is positioned beneath the engine and tender, with parts broken away. Fig. 2 is a similar view in side elevation. Fig. 3 is an end elevation of that portion of Fig. 2 which lies above the line $x-x$, looking from 35 right to left, and with parts omitted. Fig. 4 is a side elevation, partly in section, of one of the air distributers, and its associated parts, with parts broken away. Fig. 5 is a 40 fragmentary end elevation of Fig. 4, looking from right to left. Fig. 6 is an end elevation of the same looking in the opposite direction.

Referring now more particularly to the 45 drawings, reference numeral 1 designates the main reservoirs, which may be of the usual form, and which are kept constantly filled with air by means of the compressor, indicated at 2. The pipe 3 connects the said 50 reservoirs to each other and the pipe 3^a connects the compressor to one of the said reservoirs. I have shown two of the main reservoirs 1, for the reason that the air is somewhat heated as it passes from the compressor 55 to the nearest reservoir, and as the

air passes through the pipe 3 and into the other reservoir it more nearly assumes its original temperature. It is understood, however, that I do not confine myself to a plurality of the said reservoirs. Extending 60 from one of the said reservoirs is the pipe 4 which is led to and communicates with the engineer's valve 5^a, the various turns in the said pipe 4 being accomplished by means of suitable elbows such as shown at 5. Extending 65 downwardly from the engineer's valve is the pipe 6 which communicates with the straight air pipe 7, the latter extending throughout the entire length of the train, including the locomotive and tender. The pipe 70 7 is connected to the air distributers 8, by means of the pipes 9. The said distributers are in the form of hollow cylinders, the ends of which are closed by means of the plates 10, bolted at 10^a to the flange 11, upon one 75 of the ends of the said distributer, and the caps 11^a which are similarly bolted, at 12 to the opposite end of the distributers. The main body of each distributer is of smaller 80 diameter than that of the said caps, and to one of the ends of each of the distributers is connected a pipe 13, which communicates with the auxiliary air reservoirs 14.

Extending from the cap 11^a and the main body of the distributer, are the brackets 15, 85 by means of which the said distributers may be secured to the under side of the coaches. Slidable within the main body of the distributer is the hollow piston 16, around which may be suitable packing rings, 90 as indicated at 17. The right hand end of the said piston is open with respect to the interior of the distributer, and the opposite end of the piston is closed by the end wall 18, which extends beyond the limits of the said 95 piston and is slidable within the cap 11^a, the packing rings 19 being provided around the periphery of the said piston, to prevent leakage therefrom. At the center of the 100 said end wall may be the projection 20 which is adapted to contact with the cap 21^a which covers one end of the buffer spring 21, during the sliding movement of the said piston, and the opposite end of the said spring bears 105 against the screw cap 21^b. Within one side of the cap 11^a and the main body of the distributer is the bypass 22, one end of which communicates with the annular groove, indicated at 23, around the piston 16, and its 110 opposite end communicates with the inte-

rior of the cap 11^a by means of the relatively small aperture indicated at 24. The annular groove 23 communicates, by means of the small opening 25, with the interior of the hollow piston 16, so that if the said piston should at any time turn with respect to the distributor, communication would nevertheless be maintained between the interior of the cap 11^a and the interior of the said piston. Connected to each of the said distributors are the pipes 26 which also communicate with the cylinders 27, within which are the helical springs 28, of which one end of each bears against an end wall 29 of a cylinder 28, and the opposite end of the spring bears against a piston head 30, extending from which is the stem 31, which is connected, in any approved manner, to the brake beam. The straight air line extends throughout the entire length of the train and, the distributors 8, and their described connections, occur on each car. The junc-
tions of the pipes 9 and 26 with the distributors 8 are near each other, (see Fig. 4), and around the hollow piston 16 is the rather wide annular recess, indicated at 32, whereby the pipes 9 and 26 are always in free communication with each other when the parts are in the positions shown in Fig. 4, and, when the parts are so positioned, it is clear that, by turning the lever 33 of the engineer's valve 5^a, the air from the main reservoir 1 is free to flow directly from the main reservoir straight to the brake cylinders 27. It is not thought that any particular description of the engineer's valve is here necessary for the reason that it differs in no way from any such valve and the sole function of which is to direct the flow of air from the pipe 4 into either the pipes 35 or 6, and to vent either of the said pipes. Extending also throughout the entire length of the train is the automatic line 34, which is connected, by means of the pipe 35, to the engineer's valve 5^a. By means of the fitting 36, the branch pipe 37 is connected to the pipe 35, and the said branch turned at 37^a and 37^b, and finally connected to the engineer's valve 5^a. 38 indicates a check valve in the branch pipe 37, and 39 indicates a reducing valve. Communicating with the pipes 6, 4 and 35 respectively, are the pipes 40, to the upper end of each of which is connected a suitable gage such as shown at 41. The automatic line 34 is connected to the various caps 11^a by means of the pipes 42.

The operation of the device is as follows: To charge the various auxiliary reservoirs 14, the air from the main reservoir 1 is allowed to flow out through the pipe 4, through the engineer's valve 5^a, around through the pipe 37, downwardly through the pipe 35, into the pipe 34, through the pipe 42, and thence into the caps 11^a. The

entrance of the air into the interior of the caps 11^a forces the end wall 18 of the piston 16 into its position as shown in Fig. 4, which allows the air to feed on through the narrow opening 24, into the bypass 22, thence into the annular channel 23, through the opening 25 into the hollow piston 16, and finally out through the pipe 13 and into the auxiliary reservoir 14. Air is forced through the route just traced, until the indicator 75 upon the gage 41 which is connected to the pipe 35 rests at a pressure of say 70 pounds. It will be seen that, notwithstanding the pressure on both sides of the end wall 18 is the same, nevertheless the piston 16 will always be positively held in its position as seen in Fig. 4, because the face of the end wall 18 which lies within the cap 11^a is larger than that face which is exposed to the pressure of the air from within the hollow piston 16. Due to the check valve 38 the air cannot return through the pipe 37, but must be vented by allowing it to pass out through the upper end of the pipe 35 and through the engineer's valve 5^a. The pressure within the main reservoir, is, say 90 lbs., and for this reason the reducing valve 39 is used to produce the pressure of 70 pounds within the auxiliary reservoirs 14.

From the foregoing it is clear that there can be no dragging of the brakes, due to any movement of the hollow pistons 16, as the same are positively held in a position to prevent any escape of air from the auxiliary reservoirs 14 into the pipes 26. This is an important feature as the use of delicately balanced pistons or other such devices, corresponding to the pistons 16, allows air to escape intermittently from the auxiliary reservoirs and into the pipes which lead to the brake beam, which causes an undesirable chattering of the brakes against the traction wheels, and a resultant loss of power. The reason for this is that in systems now known to the art, so far as I am aware, the member which corresponds to the hollow piston 16, is too sensitive, and the small leaks which are unavoidable in the numerous joints in the train line and its connections, are intermittently opened and closed by the jar upon the coaches when the train is running.

The operation of the automatic air is that, as the fluid pressure is reduced within the pipe 35, either by the operation of the engineer's valve, or by a parting of the train and resultant rupture of the pipe 34, or other cause, the pressure upon the left hand face of the end wall 18 is correspondingly reduced, which allows the hollow piston 16 to move to the left, because of the greater pressure 125 on the right hand face thereof, until the projection 20 contacts with the buffer spring 21^a, which allows the air within the auxiliary reservoir 14 to pass through the pipe 13, into the hollow cylinder 8 and out 130

through the pipe 26 to the brake cylinder 27, which instantly causes a setting of the brake.

In the operation of my improved system there is absolutely no need of causing the 5 automatic portion thereof to be brought into use at any time, by the operation of the engineer's valve, because the entire train can be instantly brought to a full stop, and otherwise fully controlled by means of the 10 straight air line 7, which I will now describe.

The straight air line 7 is normally kept vented, and when it becomes necessary to put on the brakes, either to slow down the 15 train or to entirely stop it, all that is necessary is to operate the lever 33 of the engineer's valve 5^a, so as to allow the air from the pipe 4 to flow into the pipe 6, thence into the pipe 7, upwardly through the pipe 20 9, into the wide annular channel 32, and finally into the pipes 26 and cylinders 27.

In the systems now known to the art, so far as I am aware, the automatic air is used to control the brakes, when it is desired to 25 bring the entire train to a stop, for the reason that the straight air acts only upon the wheels of the engine and tender and is not sufficient to stop the entire train. It frequently occurs that, in the use of the systems 30 now in vogue, the air in the auxiliary reservoirs becomes completely exhausted from repeated applications, and necessity immediately thereafter arises for bringing the train to a full stop, which, of course, is impossible 35 because there is no air left in the auxiliary reservoir and the straight air system only affects the wheels of the engine and tender and can not therefore be relied upon to stop the train. In my improved system it is 40 clear that no such state of affairs could ever exist, because the train can always be stopped so long as there is air in the main reservoir.

The use of the check valve 38 intermediate

the auxiliary reservoirs 14 and the compressor 2, manifestly allows repairs to the compressor, should the same become inoperative from any cause, and these repairs could be made without stopping the train.

Attention is called to the fact that during 50 the operation of the straight air, the automatic air may be applied at any time. For example, the conductor, or other person within any of the coaches, may apply the automatic air at any time, notwithstanding 55 the fact that the engineer may, at the same time be applying the straight air to control his train in descending a grade, or for other cause.

While I have shown and described a particular form of embodiment of my invention, I am aware that many changes therein will readily suggest themselves to others skilled in the art, without departing from the spirit and scope of the invention, and I do not, 60 therefore, desire to be limited to the exact form hereinabove described and shown in the accompanying drawings.

What I claim as new and desire to protect by Letters Patent, is—

The combination in an air-brake system having both straight and automatic air lines, of a hollow piston having unequal faces and an annular channel around the said piston with which the said straight air line communicates, the said piston being acted upon by the air in an automatic line to normally prevent movement of the piston, a pipe which leads from the working chamber of the said piston to the brake cylinder and 70 which is adapted to be placed in communication with a straight air-line pipe by means of said annular channel around said piston.

PATRICK COMERFORD.
